UNITED STATES PATENT OFFICE.

GEORGE W. WEBER, OF NEW YORK, N. Y., ASSIGNOR TO AMERICAN CAN COMPANY, OF NEW YORK, N. Y., A CORPORATION OF NEW JERSEY.

MEANS FOR APPLYING HANDLES TO SHEET-METAL VESSELS.

No. 846,435.

Specification of Letters Patent.

Patented March 5, 1907.

Original application filed December 6, 1905, Serial No. 290,510. Divided and this application filed August 3, 1906. Serial No. 329,008.

To all whom it may concern:

Be it known that I, GEORGE W. WEBER, a citizen of the United States, residing in New York, in the county of New York and State of New York, have invented a new and useful Improvement in Means for Applying Handles to Sheet-Metal Vessels, of which the following is a specification.

My invention relates to improvements in means for applying handles to sheet metal vessels.

My invention consists, in connection with a sheet-metal vessel, to which the handle is applied, provided with a recess or depression on its inner side and a straight partially-round pivot-socket having openings at the ends thereof for insertion of the straight pivot members of a wire handle, of a wire handle having pivot members inserted through said openings and fitting in said socket, said vessel having on the inside at the portion thereof to which the handle is applied a cap-groove and a supplemental cap soldered thereto to prevent leakage at the pivot-openings of the socket.

My invention also consists in the novel construction of parts and devices and in the novel combination of parts and devices herein shown and described.

In the accompanying drawing, forming a part of this specification, Figure 1 is a side elevation of a sheet-metal vessel embodying my invention. Fig. 2 is a detail section on line 2 2 of Fig. 1. Fig. 3 is a detail section on line 3 3 of Fig. 2. Fig. 4 is a detail section on line 4 4 of Fig. 3. Fig. 5 is a detail view of the wire handle or bail, showing the same with its pivot members open or separated and ready to be applied to the pivot-socket of the vessel. Figs. 6 and 7 are detail views of the reinforcing-plate, and Fig. 8 is a detail section on line 8 8 of Fig. 1.

In the drawing, A represents a sheet-metal can or vessel having a body A' and upper head A'', to both of which my improved wire handles or bails B are preferably applied for convenience in handling and tilting the cans or vessels A, which are frequently of large size. To secure the wire handle B rigidly and firmly to the vessel A, I provide it on the inside thereof with a rectangular recess or depression a' and with an integral pivot

socket or channel a'', having openings a''' at its ends to receive the pivot ends or members b of the wire handle or bail B. The wire handle or bail B is provided with a reverse bend b' at its middle portion to open apart, spread, or separate the pivot ends b b sufficiently to adapt them to enter the socket-openings a''' a''' at the extremities of the pivot-socket a'' on 60 the vessel A. When this reverse bend b' is again straightened out or partially straightened out, the pivot ends of the handle are thus inserted through the openings a''' a''' in the vessel and the pivot ends again brought 65 into alignment with each other. The recess or depression a' on the inner side of the vessel which receives the reinforcing-plate forms a raised portion a'' on the outside of the vessel, and when the handle is turned down, as 70 shown in dotted lines in Fig. 2, the handle surrounds this offset or raised portion, so that the raised portion does not prevent the handle from folding or turning down flat. The raised or offset portion a'' may preferably 75 be as large as will permit the handle to surround the same when turned or folded down.

D is a reinforcing-plate which is preferably employed, the same being preferably of rectangular form and which fits in the recess a', 80 formed on the inside of the vessel, and within the marginal wall a of said recess and which is provided with a longitudinal channel or groove d, having flanges or shoulders d' d' at the middle portion thereof for the extremities 85 of the pivot members b b of the handle to abut against, and thus prevent the slipping of the handle in respect to the vessel or receptacle A. The reinforcing-plate D is also preferably furnished with an integral flap or 90 fold D', which after the parts are assembled is stamped or closed down against the plate D, and thus embraces and covers the pivot portion of the handle. The reinforcing-plate D, fitting in the recess a' of the can or 95 vessel and having the groove or channel d to receive the pivot portion of the handle, not only serves to lock and hold the handle in place, but also distributes the strain of the handle over the recess portion of the can or 100 vessel, and thus prevents the handle from tending to draw out or break the sheet metal of the can or vessel at the openings a''' a''' therein through which the pivot ends of the

- handle are inserted and against the surrounding margins of which openings the strain of the handle would chiefly come but for the plate D, interposed between the pivot members of the bail or handle and the recessed portion of the vessel or receptacle A. The recess or depression a' in the portion of the vessel A to which the handle is to be applied is preferably in depth substantially 5 half the diameter of the wire handle, so that the pivot socket or channel a^2 for the handle-wire need only be in depth about half the diameter of the handle-wire. The recess a' thus obviates the necessity of making the 10 socket-groove a^2 in depth the full diameter of the handle-wire and prevents excessive strain upon and danger of breaking the stock in the stamping operation.

I provide the portion of the vessel to which 20 the handle is to be applied with a supplemental cap F, soldered or otherwise secured thereto and preferably upon the inside thereof. A cap-groove a^3 is formed on the inside of the vessel to receive the rim or 25 flange of the cap F, the cap being preferably a solder-hemmed cap to facilitate its being readily soldered in place by machinery, as I prefer to secure the cap F in place by soldering. The cap F, soldered or otherwise tightly 30 secured on the vessel, thus prevents leakage at the socket-openings a^3 for the handle.

This is a division of my original application, Serial No. 290,510, filed December 6, 1905.

35 I claim—

1. The combination with a sheet-metal vessel provided with a recess of depression on the inner side, and a pivot-socket having openings at the ends thereof for insertion of 40 the pivot members of a wire handle, of a wire handle having pivot members inserted through said openings and fitting in said socket, said vessel having on the inside at the portion thereof to which the handle is applied a cap-groove and a supplemental cap 45 soldered thereto, substantially as specified.

2. The combination with a sheet-metal vessel provided with a recess or depression on its inner side, and a straight pivot-socket having 50 openings at the opposite ends thereof for insertion of the pivot members of a wire handle, of a wire handle having straight pivot members inserted through said openings and fitting end to end in said socket, and a cap soldered on the inside of the vessel at the portion 55 thereof to which the handle is applied to prevent leakage at the socket-openings for the handle, substantially as specified.

3. The combination with a can or receptacle provided with an integral pivot-socket 60 having openings at the opposite ends thereof for insertion of the pivot members of a wire handle, of a spring-wire handle having straight pivot members inserted through said openings and fitting end to end in said 65 socket, said handle having a middle portion provided with a reverse bend toward the pivot members and a cap secured on the inside of the vessel at the portion thereof to which the handle is applied to prevent leakage at the socket-openings, substantially as 70 specified.

4. The combination with a sheet-metal vessel provided with a cap secured thereto at the portion thereof to which the handle is to 75 be applied, of a part-round pivot-socket for the pivot members of the handle, having openings at the opposite ends thereof for insertion of the pivot members of a wire handle, and a wire handle having open or separated 80 straight pivot members inserted through said openings at the ends of the pivot-socket and fitting end to end in said pivot-socket, said handle having a middle portion provided with a reverse bend toward the pivot 85 members, substantially as specified.

5. The combination with a sheet-metal vessel provided with a cap secured thereto at the portion thereof to which the handle is to be applied, of a pivot-socket for the pivot 90 members of the handle having openings at the ends thereof for insertion of the pivot members of a wire handle, and a wire handle having open or separated pivot members inserted through said openings at the ends of 95 the pivot-socket and fitting in said pivot-socket, and lips or shoulders in said pivot-socket for the extremities of the pivot members of the handle to abut against, substantially as specified.

100 6. The combination with a sheet-metal vessel having an open-ended pivot-socket to receive the straight pivot members of a wire handle, of a wire handle having straight pivot members fitting in said sockets, a shoulder in 105 said socket at the middle portion thereof for the ends of the pivot members of the handle to abut against, and a supplemental cap secured to the vessel at the portion thereof to which the handle is applied, substantially as 110 specified.

GEORGE W. WEBER.
